[57] CLAIM

The ornamental design for a rodless cylinder with a movable table, as shown and described.

DESCRIPTION

FIG. 1 is a top plan view of a rodless cylinder;
FIG. 2 is a front elevational view thereof, showing a table located at a left end within its movable range;
FIG. 3 is a bottom plan view thereof;
FIG. 4 is a rear elevational view thereof;
FIG. 5 is a left side elevational view thereof;
FIG. 6 is a right side elevational view thereof;
FIG. 7 is a perspective view thereof; and,
FIG. 8 is a front elevational view thereof, showing the table located at a right end within its movable range.
